UNITED STATES PATENT OFFICE.

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
LONDON, ENGLAND.

ORDNANCE.

1,315,363.

Specification of Letters Patent.

Patented Sept. 9, 1919.

Application filed July 7, 1917. Serial No. 179,268.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance, of which the following is a specification.

This invention relates to ordnance of the kind having means whereby the gun can be depressed to a convenient angle for loading without disturbing the sights, the said means comprising a pivoted member between which and the gun cradle suitable gearing (termed the elevating loading gear) is disposed and which is displaced by the elevating gear to elevate the gun and the sights together; the portions of the said member that are contiguous to its pivotal axis are disposed between the gun cradle and the carriage side cheeks. The invention is particularly applicable to naval guns of the casemate or upper deck type, but it may also be employed in connection with guns other than those mounted on ships.

According to the present invention the said pivoted member in one construction comprises a cradle which surrounds the gun cradle and to which the latter is trunnioned. The inner or gun cradle may be of the usual form and carries the recoil and run out gear, and the other or outer cradle carries the sighting apparatus and also the elevating rack; in cases in which elevation indicating gear (comprising two pointers one moved from a distance and the other by the movements of the gun in elevation) is employed the outer cradle also carries the recording rack appertaining to this gear. In this manner it is not only possible to move the gun to and from its loading position without disturbing the sighting apparatus, but when it is desired to run the gun inboard for housing, the sights, the elevating rack, and the rack of the elevation indicating gear do not move inboard with the gun, as these parts are carried on the outer cradle, the only parts which move inboard being the gun cradle, the recoil and run out gear and the gun. By this arrangement the sights, the elevation indicating gear and the elevating gear, are in no way disturbed when the gun is being run inboard.

In order that the said invention may be clearly understood and readily carried into effect, we will describe the same more fully with reference to the accompanying drawings, in which:

Figure 1 is a sectional side elevation of a gun mounting viewed from the left hand side showing a constructional form of our invention.

Fig. 2 is a transverse vertical section of Fig. 1, the section of the two cradles being taken approximately on the line 1, 1 of Fig. 1.

Fig. 3 is a side elevation of the rear parts of the gun and the cradles as viewed from the right hand side.

Fig. 3^a is a half section taken approximately on the line 2, 2 of Fig. 1.

In these figures A is the gun and A' is the gun cradle. a, a are the gun cradle trunnions and a', a' are the carriage side cheeks. B is the aforesaid pivoted member which is in the form of a cradle. B' is the elevating rack attached to this member and b' is the elevating pinion gearing with the said rack. A rack C (herein termed the elevating loading rack) is connected to the member B while an operating hand wheel C' (herein termed the elevating loading hand wheel) and the gearing connecting it to the said rack are carried by the gun cradle A'. The member B need extend only a short distance in front of and behind the gun trunnions, but in order that the elevating loading hand wheel C' may be arranged near the breech end of the gun as shown, the elevating loading rack C forms part of or is connected to a bar or bracket C² extending rearward from the said member B.

In the construction shown by Figs. 1 to 3^a, the gun cradle trunnions a, a are disposed in bearings in the outer cradle B and the latter is provided with trunnions b, b disposed in bearings in the carriage side cheeks a', a'. The said bearings in the outer cradle are constituted by blocks a^{xx} (see Fig. 3^a) which are slidably mounted in longitudinal recesses in the outer cradle and are locked in these recesses in any suitable manner to enable the gun cradle to be run inboard as aforesaid. b² is the aforesaid rack of the elevation indicating gear which rack is carried by a bar b³ extending rearwardly from the left hand side of the outer cradle B.

The gun is elevated in the usual way by an elevating number of the gun's crew who is situated on the left hand side of the gun, the elevating hand wheel B^2 being arranged beneath the eye piece of the telescope B^3 . When this hand wheel is operated, the two cradles move together, the gun and cradles moving on the trunnions b , b of the outer cradle. In order to bring the gun to the loading angle when the gun has been elevated, the elevating loading hand wheel C' situated at the right hand side of the mounting is operated and imparts movement to a pinion C^3 gearing with the elevating loading rack C , thereby depressing the gun cradle A' , the outer cradle meanwhile remaining stationary owing to the fact that it is held in position by means of the elevating rack B' and its operating gear. The result is that, as the outer cradle B does not move when the gun is being brought to the loading angle, the sighting apparatus, which is carried by the outer cradle and which may have already been set for range, is not disturbed, that is to say the telescopes are not moved off the target. The elevation indicating gear (which also may have been set for range) is also not disturbed, owing to the fact that the rack b^2 is rigidly attached to the outer cradle. The gun cradle A' normally rests and is carried on a seating machined at the rear of the outer cradle B thereby forming a stop which insures that the gun cradle shall always be brought back from its loading position to a definite position in relation to the outer cradle.

The type of gun mounting with which the invention is shown employed is that heretofore proposed by us in which the carriage side cheeks a' , a' are extended downward to the deck so as to accommodate between them the elevating and training numbers. In this case each of the sighting telescopes may be arranged between the inner trunnion a and the outer trunnion b , as shown, the outer cradle B being formed with suitable openings B^x , B^x (see Fig. 2) to accommodate the telescopes B^3 , B^3 so that the axis of the trunnions b , b preferably intersects the axes of the telescopes; the telescopes may however be arranged in any other convenient position.

The elevating number and the elevating loading number may be accommodated on platforms B^4 , B^5 moving with the gun in training. The platform B^5 also serves to accommodate the training number who operates the training hand wheel B^6 , and the platform B^4 also serves to accommodate an auxiliary elevating number who operates the auxiliary elevating hand-wheel B^{6x} . Instead of platforms seats may be provided.

What we claim and desire to secure by Letters Patent of the United States is:—

65 1. In ordnance, the combination with the

gun carriage and the gun cradle, of a second cradle surrounding said gun cradle, means for trunnioning the gun cradle to the second cradle, means for trunnioning said second cradle to the gun carriage, elevating gear operating upon said second cradle for moving the gun and sights together and gearing interposed between the two cradles for moving the gun independently of the sights. 75

2. In ordnance, the combination with the gun carriage and the gun cradle, of a second cradle surrounding said gun cradle, trunnions on the gun cradle for engaging with the second cradle, trunnions on said second cradle for engaging with the gun carriage, elevating gear operating upon said second cradle for moving the gun and sights together and gearing interposed between the two cradles for moving the gun independently of the sights to a convenient angle for being loaded. 80

3. In ordnance, the combination with the gun carriage and the gun cradle, of a second cradle surrounding said gun cradle, means for trunnioning the gun cradle to the second cradle, means for trunnioning said second cradle to the gun carriage, elevating gear operating upon said second cradle for moving the gun and sights together, gearing interposed between the two cradles for moving the gun independently of the sights, and elevation indicating gear comprising a member attached to said second cradle. 90

4. In ordnance, the combination with the gun carriage and the gun cradle, of a second cradle surrounding said gun cradle, means for trunnioning the gun cradle to the second cradle, means for trunnioning said second cradle to the gun carriage, elevating gear operating upon said second cradle for moving the gun and sights together, gearing interposed between the two cradles for moving the gun independently of the sights, a member extending rearward from said second cradle, and elevation indicating gear comprising a rack attached to said member. 105

5. In ordnance, the combination with the gun carriage and the gun cradle, of a second cradle surrounding said gun cradle, trunnions on the gun cradle for engaging with the second cradle, trunnions on said second cradle for engaging with the gun carriage, elevating gear operating upon said second cradle for moving the gun and sights together, gearing interposed between the two cradles for moving the gun independently of the sights to a convenient angle for being loaded, and a sight disposed in an opening in said second cradle. 115

6. In ordnance, the combination with the gun carriage and the gun cradle, of a second cradle surrounding said gun cradle, trunnions on the gun cradle for engaging with the second cradle, trunnions on said 120

125

130

second cradle for engaging with the gun carriage, elevating gear operating upon said second cradle for moving the gun and sights together, gearing interposed between the 5 two cradles for moving the gun independently of the sights to a convenient angle for being loaded, side cheeks of the gun carriage extending downward to the deck and sights disposed in openings in the portions

of said second cradle contiguous to its trunnions.

In testimony whereof we have hereunto affixed our signatures.

ARTHUR TREVOR DAWSON.
GEORGE THOMAS BUCKHAM.
